UNITED STATES PATENT OFFICE.

OMA CARR, OF NEW YORK, N. Y.

PROCESS OF MANUFACTURING OF LEATHER.

1,230,667.

Specification of Letters Patent. Patented June 19, 1917.

Application filed November 6, 1915. Serial No. 59,927.

To all whom it may concern:

Be it known that I, OMA CARR, a citizen of the United States of America, and a resident of New York, county of New York, and State of New York, have invented certain new and useful Improvements in Processes of Manufacturing of Leather, of which the following is a full and clear specification.

In the tanning of hides by the so-called "vacuum" processes, the objective is a movement of liquid within the hide fabric, induced by boiling the tanning liquor in which the hide is submerged, under reduced pressure and at a temperature at which the hide substance is not decomposed. Such intercellular circulation depends for its activity upon the vigor of the boiling, and it is desirable that the hide and tanning liquor be so related that all parts of the hide shall be at the same temperature. My invention relates to a process of tanning under reduced pressure under conditions assuring equal temperature over the whole spread of the hide.

25 In the drawings—

Figures 1 and 2 are views of one form of apparatus for carrying out my improved method; and

Fig. 3 a vertical sectional view in diagram 30 of an apparatus for illustrating another way of carrying out my method.

I overcome the above mentioned faults by removing the hydrostatic head. Referring to Figs. 1 and 2 of the drawing annexed, it will be seen that the liquor level (2) is at a considerable distance below the stock (1), which is suspended from the sticks or supports (3). If, now, the chamber is pulled to a vacuum of 28", the liquor below the level (2) dropt to 105°, and by means of a circulating pump A on line (4) the liquor is sent through showers (5) over the stock, the liquor will cover the stock by spreading over it, but without material thickness, or hydrostatic head. Obviously the pressure is the same, practically, upon all parts of the stock surface, and the boiling-point of the intercellular liquid sensibly the same in all such parts—the same at the shank (6) as at the back line (7)—which is distinctly not the case where the stock is hung submerged in the liquor, with the level (2) of the latter considerably above the stock. It is therefore practically correct to say that if there be a vacuum of 28" inches in the chamber,

the boiling-point of the intercellular liquid is 100° F. in all parts of the hide.

It is now apparent that the stock, hung in a chamber carrying a vacuum of 28 inches, may be showered by the tanning liquor at any desired temperature without raising the temperature of the intercellular liquid above the boiling-point incident to 28 inches vacuum—the heat of the liquor will "flash" out under the reduced pressure, causing the intercellular liquid to boil and thus produce the intercellular circulation desired. With this circulation operating, the liquor flooding over the stock will be drawn in, carrying its tannin for absorption by the fiber.

It is practicable to bring the liquor to be showered over the stock from any source—the bottom of the chamber, from a preceding chamber, or from an exterior source—and at any desired temperature, according to the vacuum employed and condition of the hide fiber as to the resistance to heat. Neither do I confine myself to showers for distribution or circulation of the liquor over the stock to obtain the absence of material hydrostatic head, as such distribution or circulation may be secured by various convenient means; as, for example, the apparatus illustrated in Fig. 3, where the stock is immersed in the liquor with level at 2, then hoisted (as shown in dotted lines) into the vacuum space, where the heat flashes out and causes the intercellular boiling, the alternation of immersion and hoisting being sufficient to provide the absence of material hydrostatic head. Similarly, where cut-soles, blocks, strips, etc., are to be tanned, the stock may be placed in shallow trays, the depth of which will not be sufficient to create an undesirable hydrostatic head a few inches of liquor not causing an undesirable range of boiling-point from bottom to surface.

My process renders practicable the tanning of the stock on either the alkaline or acid side—that is, the limed and dehaired hide, "lime plump" may be tanned out in a tannin solution made alkaline; after the tanning is completed the fabric may be brought over to the acid side by treatment in a fluid containing a suitable acid—lactic, butyric, acetic, etc. By such manipulation the lime in the dehaired hide may be ignored, and the usual need for the neutralizing of such lime, and bringing of the stock to the "acid plump" condition, avoided; and the com-

pleted stock may be brought out as plump as the limed stock from which it is tanned—the practical importance of which is very great. On such “alkaline-side” stock, a 5 water-proofing solution based upon waxes, resins, caseins, etc., soluble in alkali, may be conveniently used, the following acid treatment assuring the fixation of such materials within the fabric, as well as the bleaching 10 of the surfaces. When the stock is to be tanned on the “acid-side”, the composition of the tanning liquor may be arranged to provide the usual change from the “lime plump” to “acid plump” condition of the 15 fiber, such combination depending upon the tanning material employed.

My process also renders practicable the manufacture of cut-soles, blocks, strips, bends, butts, etc., by reversal of the conventional process of first tanning, finishing and rolling the leather, and then cutting into the desired sections. For this purpose, the hide 20 in any state of preparation or partial tanning may be cut into the desired sections—cut-sole, block, bend, etc.—and then tanned 25 by my process, very great economy in handling and tanning material, besides important improvements in quality, being obtained.

30 I now proceed with my process thus: The prepared hide, at whatever stage of preparation, is placed in the vacuum chamber, vacuum pulled up, and the tanning liquor circulated over the hide in such manner that 35 there is no undesirable hydrostatic head, the liquor being at any temperature desired, and being taken from any source desired. When the tanning is complete, the stock may be finished conveniently; or, the liquor may be 40 withdrawn and a water-proofing solution run in, vacuum maintained, and temperature carried high enough to boil out the intercellular liquid; (if the stock has been tanned on the “alkaline side”, it may be brought to 45 the “acid side” by a suitable acid bath or treatment, before or after water-proofing). The stock is then finished as desired.

It will be understood that when “prepared 50 hide” is referred to herein, there is meant hide in any state of preparation—in the “white”, or “plumped”, or “colored”, “cat”, “blocked”, or in any state of preparation at which it may be desired to begin the use of my process. Also, any of the steps of my 55 process may be interrupted or suspended for purposes of incidental manipulation—as in the production of split leathers, where the hide, at a desired stage of tanning, may be removed from the process for splitting, and 60 the stock may be withdrawn for bleaching, if desired, or a bleaching step used. Also, any of the steps of my process may be divided—for example, two or more different tanning liquors may be employed, the absorption 65 step being divided to permit such;

or the liquor may be withdrawn for enrichment or alteration; or, several chamber may be connected in a series, liquor being circulated from one to another. Furthermore, as the leather approaches complete tanning, 70 it will withstand higher temperature, and such stage of the absorption step may, if desired, be conducted at higher temperature and lower vacuum.

I wish it understood also that it is not 75 essential in all cases to heat the main mass or body of the tanning liquor to boiling point, since in some cases it will be sufficient to bring the interior of the tank to a sufficiently high temperature to boil or flash 80 simplify the thinner liquor within the fabric. In fact, it is impracticable to prescribe any definite temperature, as many contingencies must be taken into account in determining the temperature of the vacuum space. 85 Neither is it completely essential that the intercellular liquid should boil explosively, as it may be merely agitated by the escape of the heat and so induce inward movement of the exterior liquor. Intercellular movement 90 is the important thing, whether it be actual boiling or simple circulation due to the heat currents. Boiling would bring about a more rapid circulation, but is not necessarily best in all cases; for instance, 95 young stock (with much white fiber still in it) may do better with the milder circulation, while stock already fairly tanned may need active intercellular boiling. The removal of the hydrostatic head expedites 100 intercellular circulation in both cases and is, therefore, the essential feature of my method.

Having thus described my invention, what I claim is:

1. The process of tanning leather herein described, consisting in maintaining a partial vacuum in a tanning chamber containing the prepared hide and a tanning liquor, maintaining circulation of the liquor over 105 the hides without appreciable hydrostatic head thereon and heating the liquor sufficiently to cause intercellular agitation and consequent absorption of the tannin by the hide.

2. The process of tanning leather herein described, consisting in maintaining a partial vacuum in a tanning chamber containing the prepared hide and a tanning liquor, maintaining circulation of the liquor over 110 the hides without appreciable hydrostatic head thereon, and heating the liquor sufficiently to cause intercellular agitation and consequent absorption of the tannin by the hide.

3. The process of tanning leather herein described, consisting in maintaining a partial vacuum in a tanning chamber containing the prepared hide and a tanning liquor, maintaining circulation of the liquor over 115 120 125 130 135

the hide without appreciable hydrostatic head thereon, heating the liquor sufficiently to cause intercellular agitation and consequent absorption of the tannin by the hide, 5 circulating over the leather so produced and while the same is still hot and wet a water-proofing solution until its absorption by the leather, and then finishing the leather.

4. The process of tanning leather herein 10 described, consisting in maintaining a partial vacuum in a tanning chamber containing the prepared hide and an alkaline tanning liquor, maintaining circulation of the liquor over the hide without appreciable 15 hydrostatic head thereon, and heating the liquor sufficiently to cause intercellular agitation and consequent absorption of the tannin by the hide.

5. The process of tanning leather herein 20 described, consisting in maintaining a partial vacuum in a tanning chamber containing the prepared hide and an alkaline tanning liquor, maintaining circulation of the liquor over the hide without appreciable 25 hydrostatic head thereon, heating the liquor sufficiently to cause intercellular agitation and consequent absorption of the tannin by the hide, acidifying the leather fabric so produced while the same is still wet and 30 hot.

6. The process of tanning leather herein 35 described, consisting in maintaining a partial vacuum in a tanning chamber containing the prepared hide and an alkaline tanning liquor, maintaining circulation of the liquor over the hide without appreciable hydrostatic head thereon, heating the liquor sufficiently to cause intercellular agitation 40 and consequent absorption of the tannin by the hide, acidifying the leather fabric so produced while the same is still wet, circulating over the leather while the same is still wet and hot a water-proofing solution until its absorption by the leather.

45 7. The process of tanning leather herein described, consisting in maintaining a partial vacuum in a tanning chamber containing the prepared hide and an alkaline tanning liquor, maintaining circulation of the 50 liquor over the hide without appreciable hydrostatic head thereon, heating the liquor sufficiently to cause intercellular agitation and consequent absorption of the tannin by the hide, acidifying the leather fabric so 55 produced while the same is still wet, circulating over the leather while the same is still wet and hot an alkaline water-proofing solution until its absorption by the leather.

8. The process of tanning leather herein 60 described, consisting in maintaining a partial vacuum in a tanning chamber contain-

ing the prepared hide and a tanning liquor, maintaining circulation of the liquor over the hide without appreciable hydrostatic head thereon, heating the liquor sufficiently 65 to cause intercellular agitation and consequent absorption of the tannin by the hide, circulating over the leather so produced while the same is still wet a water-proofing solution until its absorption by the leather, 70 acidifying the leather while the same is still wet and hot.

9. The process of tanning leather herein 75 described, consisting in maintaining a partial vacuum in a tanning chamber containing the prepared hide and a tanning liquor, maintaining circulation of the liquor over the hide without appreciable hydrostatic head thereon, heating the liquor sufficiently to cause intercellular agitation and consequent absorption of the tannin by the hide, circulating over the leather so produced 80 while the same is still wet an alkaline water-proofing solution until its absorption by the leather, acidifying the leather while the 85 same is still wet and hot.

10. The process of tanning leather herein 90 described, consisting in maintaining a partial vacuum in a tanning chamber containing the prepared hide and an alkaline tanning liquor, maintaining circulation of the liquor over the hide without appreciable hydrostatic head thereon, heating the liquor sufficiently to cause intercellular agitation 95 and consequent absorption of the tannin by the hide, circulating over the leather so produced while the same is still wet an acid water-proofing solution until its absorption by the leather.

11. The process of tanning leather herein 100 described, consisting in maintaining a partial vacuum in a tanning chamber containing the prepared hide, maintaining a thin layer of liquid over the surfaces of the hide to thereby practically eliminate hydrostatic 105 head, and heating the tanning liquor sufficiently to cause intercellular agitation and consequent absorption of the tannin by the hide.

12. The process of tanning leather herein 110 described, consisting in maintaining a partial vacuum in a tanning chamber containing the prepared hide and a tanning liquor, spraying the liquor upon the surfaces of the 115 hide and thereby eliminating all appreciable hydrostatic head, and heating the tanning liquor sufficiently to cause intercellular agitation and consequent absorption of the tannin by the hide.

In testimony whereof I hereunto affix my signature.

OMA CARR.
